UNITED STATES PATENT OFFICE.

JAMES H. RAND, JR., OF NORTH TONAWANDA, NEW YORK.

COMPOSITE SHEET FOR INDEX-STRIPS.

1,185,538.

Specification of Letters Patent.

Patented May 30, 1916.

Application filed December 10, 1914. Serial No. 876,563.

To all whom it may concern:

Be it known that I, JAMES H. RAND, Jr., a citizen of the United States, and resident of North Tonawanda, in the county of Niagara and State of New York, have invented new and useful Improvements in Composite Sheets for Index-Strips, of which the following is a specification.

In indexes or indicators of the kind comprising a frame or panel in which a large number of adjustable and interchangeable card or paper strips are supported, bearing lists of names, or other indexed matter, much difficulty has been experienced in typewriting the desired data on the strips and in inserting them in large groups into the index panel in a predetermined orderly arrangement. The strips are usually made of heavy paper or cardboard and are relatively long and narrow. When the strips are inscribed by hand less difficulty is experienced, although even then the cards are so narrow that it is awkward to write them by hand. But when they are typewritten, as is customary and desirable both for the sake of clearness and legibility and to save time, especially in large indexes containing perhaps hundreds of card strips, it has been necessary either to use some form of special typewriter attachment for holding the individual strips on the platen in position to receive the typewriting, or to typewrite the index titles in a column on a card sheet large enough to go into the typewriter in the usual way, and then to cut or separate the large sheet into strips each containing one indexed title. In furtherance of this latter practice it has also been proposed to perforate or score the sheet in parallel lines to aid in separating or tearing apart the strips; this, however, leaves ragged edges, endangers the destruction or injury of the strips in separating them, and takes time. Furthermore, whether the strips are first cut and then printed with the aid of some special attachment, or first printed on a continuous sheet and then cut into strips, the finished printed strips are produced individually and must be put into the index frame individually and therefore slowly.

The principal object of the present invention is to overcome these objections, and to produce a composite sheet for making index or indicator strips, wherein the individual strips are clearly and completely severed one from another, but are separably

connected together by a flexible and removable binder, so that the subject-matter of the index may be typewritten on the strips composing the sheet in the same way as upon a continuous sheet of paper or cardboard, and thereafter the flexible binder may be removed leaving the several strips free and independent, but in proper order to be inserted into the index panel all together or in groups, if desired.

In the accompanying drawings which illustrate certain embodiments of the invention,—Figure 1 is a front view illustrating a composite sheet containing the invention in its preferred form; Fig. 2 is a rear view of said sheet; Figs. 3 and 4 illustrate the preferred mode of inserting the finished strips into an index panel; and Fig. 5 is a front view illustrating a modification of the invention.

The composite sheet consists of a number of relatively long and narrow index or indicator strips *a*, of paper, cardboard or other suitable material, and each of the desired dimensions for receiving the name or other inscription according to the subject-matter for which the index is to be used. These index strips are arranged side by side with their longer edges in close juxtaposition as shown, and are separably connected together in sheet form by means of one or more flexible and removable binder elements. In the form shown in Figs. 1 and 2 the binder elements consist of a pair of strips *b* of textile fabric, coated on one side with gum, mucilage or other suitable adhesive, arranged transversely of the index strips *a* and near the ends thereof, and temporarily stuck to the rear side of the series of index strips. Thus a flexible sheet is formed which may be easily bent or rolled to go into an ordinary typewriter, composed of the index strips *a* separably connected together by the flexible and removable binder strips *b*. After the subject-matter of the index has been printed on said composite sheet, the sheet is laid face down and the binder strips *b* are peeled off, the adhesive being such as to allow this without injuring the index strips, and the index strip are left wholly separated from one another, and in the same orderly arrangement in which they were printed.

If it should be desired to insert the index strips into the index frame all at once or in groups in the same order in which they

were printed, the composite sheet is placed face downward on a card or board *c* with the ends of strips *a* projecting beyond the edge of the board *c*, (Fig. 3). Then the 5 binder strips *b* are peeled off leaving the disconnected strips *a* as already described. Then another card or board *d* is laid on the strips *a* and board *c*. The index strips *a* are thus held between the two boards *c* and *d* 10 without disarrangement, and with their ends projecting clear of the boards (Fig. 3). While thus held the projecting ends of the index strips are placed all together in the usual guide channel formed by the flange *e* 15 at one side of the index frame or panel *f*. The boards *c* and *d* are then removed and the strips *a* lie on the index frame with one end under the flange *e* and the other end on the outside of the opposite flange *e'*, as 20 shown in the lower part of Fig. 4. The user then springs the overlying ends of the index strips under the guide flange *e'* in the manner indicated by the hand in Fig. 4, until all are in position as shown in the 25 upper part of Fig. 4.

In the modification shown in Fig. 5, the index strips *a* of cardboard or the like, are arranged side by side as before, but the flexible binder elements by which the strips 30 *a* are temporarily connected together to form a sheet, consist of threads or cords *g* threaded through the strips *a* edgewise. When the strips *a* are to be separated the threads or cords *g* are pulled out, leaving the 35 strips disconnected but in order, as before. As the threads or cords *g* pass through the body of the strips *a* either side of the composite sheet may be deemed the face, and no marks or stains are left by the binder elements after their removal, as might happen 40 when the binder is applied externally.

I claim:-

1. A flexible composite sheet of the character described, comprising a number of 45 relatively long and narrow index strips completely severed from and independent of one another arranged side by side with their longer edges in juxtaposition, and one or more flexible and removable binder ele-

ments extending transversely of said index 50 strips by which said index strips are separably connected, said sheet being composed of paper adapted to be received and retained by an index frame when detached from the binder elements. 55

2. A flexible composite sheet of the character described, comprising a number of relatively long and narrow index strips completely severed from and independent of one another arranged side by side with their 60 longer edges in juxtaposition, and a pair of flexible and removable binder elements arranged transversely of and near the ends of said index strips, by which said index strips are separably connected, said sheet 65 being composed of paper adapted to be received and retained by an index frame when detached from the binder elements.

3. A flexible composite sheet of the character described, comprising a number of 70 relatively long and narrow index strips arranged side by side with their longer edges in juxtaposition, and one or more binder strips of textile fabric arranged transversely of said index strips and removably secured 75 thereto by an adhesive, whereby said index strips are separably connected, said sheet being composed of paper adapted to be received and retained by an index frame when detached from the binder elements. 80

4. A flexible composite sheet of the character described, comprising a number of relatively long and narrow index strips arranged side by side with their longer edges in juxtaposition, and one or more removable binder strips of adhesive-coated textile fabric by which said index strips are separably connected, said sheet being composed of paper adapted to be received and retained by an index frame when detached 85 from the binder elements. 90

Signed by me at North Tonawanda, N. Y., this fourth day of December 1914.
